SUPPORT FOR HEAT-TREATING CONTAINER
AND CLOSURE THEREFOR

Henry H. Harris, Champaign, Ill.

Application February 27, 1943, Serial No. 477,476

6 Claims. (Cl. 263—47)

My invention relates generally to work containing receptacles, and in particular to work containing receptacles adapted to be moved through a heat treating furnace. My invention will be described in respect of a work support used in the carburizing process, but its use need not necessarily be so limited, the device being equally usable in other processes.

When conventional containers are used in heat treating furnaces, the work to be treated is placed inside the boxes and embedded in a carbonaceous material such as bone dust and the like. The boxes are then covered over with heavy trays, and inverted, with the trays on the underside, and in this position placed on skid rails or tracks within the furnace. The trays are arranged within the furnace in end-to-end or side-by-side abutting relationship and thrust applied to the rearmost tray is transmitted down to the line from tray to tray to the endmost tray. In this manner, the loaded trays are passed through the cycle in step-by-step movement until pushed out at the discharge end of the furnace.

The trays function to support the work being treated as well as the weight of the carbonaceous material; the trays serve as closures for the boxes and bear the weight of the boxes within which the work is contained, and they also serve to transmit the moving thrust from one tray to the next, down the line. In use, the trays are subjected to the rough handling incident to the process, as well as to extremely high furnace temperatures and sudden changes in temperatures, and all too often the trays develop cracks, shrinks and warpings necessitating replacement at too frequent intervals. Conventionally, both the trays and boxes have been made of thick section material, at some expense and with appreciable weight, and their failure in use involves considerable delay and attendant expense. The weight of the boxes and trays is, of course, a factor in the power needed to shift them through the furnace.

The general objective of this invention is the simplification of the apparatus used in supporting the work being treated, while retaining all the functions of the devices conventionally in use.

The main object of my invention is the provision of a work container and combined means to close same and support same during movement through a furnace. In my device, I have eliminated the heavy tray-closure used as a support, and close the container with one element and support the container on other elements to which the closure is secured.

Another object of my invention is the provision of a work container and support means therefor keyed thereto for movement through a furnace.

Still another object of my invention is the provision of a closure for a work container and support means for the container keyed onto the closure, the supports receiving and transmitting the thrust of travelling movement through the furnace.

Still another object of my invention is the provision of a closure for a work container which may be folded for insertion into the container and opened to full size thereafter to effectively seal the container.

Still another object of my invention is the provision of a closure for a work container comprising a plurality of parts hingedly secured together.

Still another object of my invention is the provision of a closure for a work container and means to support the container, the closure comprising a plurality of parts hingedly secured together and to the support means.

Further objects of my invention will appear during the course of the following description of several illustrative embodiments thereof.

In the drawing annexed hereto, and forming a part hereof,

Figure 1 is a top plan view, partly in section, of one form of device constructed according to and embodying my invention; and

Fig. 2 is a longitudinal vertical section along the line 2—2 of Fig. 1.

My device, indicated generally by reference numeral 10, comprises a pair of track- or rail-overlying shoes or skids 12, 14, of U-beam section, of substantially equal length. Shoes 12, 14 are cast or otherwise formed of high heat and corrosion resisting alloy material, and each has a surface 16 at the bottom thereof, and a pair of integrally formed vertically upstanding side walls 18, 20.

One of the shoes, as 14, may have a pair of integrally formed legs 26, 26 depending from the sides thereof, defining a channel 28. Legs 26, at each end of the shoe are flared outwardly, as at 30, to guide the shoe onto the skid rails or tracks; legs 26, 26 straddling one of the tracks or rails within the furnace to keep the shoe aligned thereon. The tops of walls 18, 20 are transversely notched in from end to end thereof, as at 40, 40. Within the trough of the U-beam members, I form a plurality of webs 55, 55 spaced apart along the length thereof, and projecting upwards of

walls 18, 20. Each web is laterally apertured near the top thereof, as at 58.

The work container component of my invention, box 60, is cast or otherwise formed of high heat and corrosion resisting alloy material, and is of generally conventional rectangular shape. Box 60 is of such width as to have the side walls 62, 62 thereof, fit into notches 40, 40 in the U-beams, as at 65. End walls 66, 66 are shouledered to form interior shelves 68 extending from side to side of the box.

A closure plate 70 is provided, consisting of a central plate 72 and a pair of wing members 74, 74, hingedly secured to the central plate. The grooves 76 in both plate 72 and wings 74 are wider than teeth 78 therein, providing spaces for the reception of the apertured tips of webs 55. The interfitting teeth 78 are all laterally cored and when these corings are aligned with web openings 58, a pin may be passed therethrough to lock closure plate 70 to the thrust beams 12, 14.

In use, box 60 is inverted, open end upwards, and charged with the work to be treated and with the carbonaceous material. Plate 70 is then fitted into the open end of the box onto the charge. One or both of wings 74 may be swung downwardly so as to permit insertion of plate 70 past shelves 68. Box walls 62 are then fitted into notches 40, 40. Box 60 may then be inverted and disposed atop a pair of parallel tracks or rails within the furnace.

Upon inversion of the box, the charge drops downward onto the three portions of the plate, and swings wings 74 down onto shelves 68 (as at the lower right hand corner of Fig. 2). This pivoting action of the wings 74, 74 into rest position atop shelves 68, 68 serves to close the container, and locked as plate 70 is to the thrust beams 12, 14, it functions to secure the box atop the beams and prevent slippage thereof during movement through the furnace.

Central portion 72 of closure plate 70 may be transversely arched, as at 82, and provided with corrugations 84 to strengthen same for load supporting purposes.

A number of loaded containers, mounted on shoes such as those hereinabove may then be disposed within the furnace in side-by-side relationship, the thrust beams of one butting against the beams of the adjacent unit. Thrust applied to the beams of the endmost unit will be transmitted down the line to move same either continuously or intermittently as desired, through the furnace. The closures take no thrust. The boxes 60 similarly do not receive or transmit any thrust, and they may, therefore, be formed of much lighter and thinner section alloy material than heretofore.

The device of my invention, as a unit, is easily assembled for use, and just as easily dismantled. Plates, boxes, beams, etc., may be formed of uniformly dimensioned size, as to be interchangeable with parts of other units. The thrust beams may be formed of extra heavy material, since they must absorb and transmit the moving thrust.

The box is, in and of itself, a rigid beam member, capable of maintaining its shape if supported at any two or more points. A heavy tray, as in conventional practice, is not at all neces-

sary to support the box, and in my invention, the thrust beams 12 and 14 support the box, the plate and the work load thereon and receive, absorb and transmit the thrust. The thrust beams and box may be formed of uniform section, and the use of these thrust beams localizing all compression strains results in much longer alloy life. A weight saving of up to 50% is possible with my device, which is operationally more efficient than the conventional arrangements.

Having now described my invention, what I claim and desire to secure by Letters Patent is:

1. A work container for use in heat treating furnaces having rails on the floor thereof, said container having a constricted opening thereunto, and furnace rail-overlying support means for the container and closure, the supports comprising a plurality of spaced apart elongated thrust beams, the closure being removably secured within the container and secured to the beams and locked thereto to maintain same in the spaced apart position both the container and the closure resting directly on the thrust beams.

2. A work container for use in a heat treating furnace having rails therewithin, the container having an opening thereinto, a pair of inturned lips on opposite sides of the container reducing the size of the opening, a closure for said opening, said closure comprising a plurality of plates pivotally secured together in horizontal alignment, the endmost plates being swingable out of alignment to permit insertion of the closure into the container, past the reduced opening, said endmost plates being reswingable into line to rest on the inturned lips to close the opening.

3. A work container and closure therefor as in claim 2, and means to support same on the furnace rails, the means comprising a plurality of elongated, rail-overlying thrust beams, means to locate and rest the container on the thrust beams, and means to secure the closure onto the thrust beams.

4. A work container and closure therefor as in claim 2, and means to support the container and closure on the furnace rails, the support means comprising a plurality of elongated, rail-overlying thrust beams, means on the thrust beams to locate and receive the container thereon in fixed position in from the ends of the rails, and means on the thrust beams interfitting with the closure permitting pivotal movement of the endmost plates thereof.

5. A work container and closure therefor as in claim 2, in which the closure comprises three plates, the end plates interfitting with the center plate and having a rod passing through the interfitting portions, about which rod the end plates may pivot with respect to the middle plate.

6. A work container and closure therefor as in claim 2, and means to support the container and closure on the furnace rails in which the closure comprises three plates, the end plates interfitting with the center plate and having a rod passing through the interfitting portions, about which rod the end plates may pivot with respect to the middle plates and means on the supporting means to engage the rod whereby the closure is removably secured to the thrust beams.

HENRY H. HARRIS.
